UNITED STATES PATENT OFFICE

HERBERT BORKENHAGEN AND AUGUST OLSON, OF CHICAGO, ILLINOIS

VAULT-LOCK PROTECTOR

Application filed June 3, 1929. Serial No. 367,917.

This invention relates to vault protecting devices, particularly protective means for the controlling dial of a combination lock to prevent unauthorized access thereto.

5 It is an object of this invention to provide an improved lock protective device which contains a noxious gas and entirely surrounds the combination dial of the lock. A key controlled cover permits access to the 10 dial by authorized persons, but any attempt to forcibly remove the cover will result in the discharge of the noxious gas.

It is a further object of this invention to provide a gas discharging means that is responsive either to a blow on the cover or a 15 movement of the mounting ring.

A further object is also to improve the locking means which secures the lock cover to the mounting ring.

20 Other and further important objects of this invention will be apparent from the disclosures in the specification and accompanying drawings.

This invention in a preferred form is illustrated in the drawings and hereinafter more fully described.

On the drawings:

Figure 1 is a fragmentary front elevation of a vault door showing the device mounted 30 over the dial of a combination lock, the cover being in the unlocked position.

Figure 2 is an enlarged plan view with the cover removed.

35 Figure 3 is an enlarged vertical section of the device with the cover in the locked position taken on line III—III of Figure 2.

Figure 4 is an enlarged vertical section of the device with the cover in the locked position taken on line IV—IV of Figure 2.

40 Figure 5 is an enlarged vertical section of the device with the cover in the locked position taken on line V—V of Figure 2.

Figure 6 is a segmental bottom view of the lock operating mechanism, taken on the line 45 VI—VI of Figure 4.

Figure 7 is an enlarged segmental vertical section of the lock operating mechanism taken on line VII—VII of Figure 6.

As shown on the drawings:

A vault door 1 is shown upon which is mounted the usual bolt operating handle 2, combination lock dial 3 and the protective device 4 which has its cover 5 swung to the normal unlocked position. With the cover in this position the combination dial is exposed, thereby permitting the vault to be 55 unlocked.

A mounting ring 6 is centered about the combination dial 3 and is held in place by means of large headed cap screws 7 extending through apertures 8 in the ring 6. These apertures are larger than the cap screws and permit the ring to be shifted a limited amount relative to the combination dial. The ring is initially mounted by means of screws 9 which are threaded into the screw plugs 10 mounted in the vault door. These screws have a contracted portion 11 which is designed to be sheared by a blow sufficient to shift the mounting ring 6 when held in place by the cap screws 7. The upper end of the mounting ring 6 has an annular groove 12 for receiving an outwardly turned flange 13 of the dome shaped cover 5. An annular plate 14 is mounted in the bottom of the groove 12 and covers a locking ring 15. The plate 14 is secured to the ring 6 by means of small cap screws 16 extending upwardly through apertures 17 in the ring.

A charged material 18, adapted to give off noxious gas when subjected to heat, is held within the dome of the cover 5 by means of a retaining plate 19 which is secured in place by a screw 20 extending through a central aperture of the plate and threadedly 35 engaging a boss in the dome of cover 5. The plate 19 has a depending annular V groove stamped therein; the inner side of which forms a conical section 21 in which are placed apertures 22 which allow the noxious gas to 90

escape from the dome. These apertures are normally sealed with wax or other material which at normal temperatures is solid. Secured to the outer side of the V groove are a plurality of threaded sleeves 23, designed to receive a blank cartridge 24 which, when fired will vaporize the noxious gas material. A firing pin 25 is held in position against the cap of the cartridge by means of a sleeve 26, which is in threaded engagement with sleeve 23. A hammer pin 27 is aligned with the firing pin 25. The hammer pin projects through an aperture in the upper end of an outer sleeve 28, which surrounds an inner sleeve 29, having said hammer pin slidably fitted into its upper end. The inner sleeve and hammer pin are moved downwardly, with respect to the outer sleeve which is securely held in the ring 6 by a set screw 30, by means of a coil spring 31, placed between the upper ends of the two sleeves. Within the inner sleeve is the screw 9, previously referred to, which forms the hammer of the firing mechanism surrounded by a spring 32. The screw 9 has a contracted section 11 where it projects through an aperture in the lower end of the inner sleeve 29. This screw is threaded into plug 10 mounted in the vault door and when tightened compresses the spring 32, as well as locates the ring 6 on the vault door.

The cover 5 is attached to the ring 6 by a guide pin 33 which is threadedly secured to the horizontal flange 13 of the cover. This guide pin extends downwardly through an aperture in the annular plate 14 and an aperture 34 in the ring 6. The lower portion of the guide pin is cylindrical in form and has an outwardly turned annular flange 35 at its lower edge extending to the wall of the aperture 34. A stop pin 36 surrounded by a coil spring 37 is positioned within the cylindrical portion of the guide pin. The lower end of aperture 34 is threaded to receive a screw plug 38 having a frangible top. It is evident, therefore, that the screw plug may be raised or lowered to limit the downward movement of the stop pin 36 and thereby adjust the space 39 between the flange 13 of the cover 5 and the annular plate 14. The cover 5 may be moved away from the ring 6 until the position is reached where the annular flange 35 of the guide pin 33 strikes the top of aperture 34. As soon, however, as the cover clears the ring 6, it is free to be rotated about the guide pin for exposing the combination dial.

Locking pins 40 are secured to the flange 13 of the cover and are adapted to enter apertures in the annular ring 14 and apertures 41 in ring 6 in alignment therewith. A piston having a depending wall 42 is contained within the aperture 41 and is movable in a longitudinal direction relative to the walls thereof. A pin 43 is centrally secured

to the top of the piston and extends downwardly therefrom to form a stop for limiting the downward movement of the piston. A coil spring 44 which is contained within the piston wall 42 and surrounds the pin 43, tends to push the piston to the upper end of the aperture 41. The lower end of the aperture 41 is threaded to receive a screw plug 45 which is similar to plug 38 and serves a like purpose.

A tumbler lock 46 vertically mounted in the ring 6 may be operated by a key which is inserted through a key guide 47 which is rotatably mounted in the flange 13 of the cover 5. Flanges on the flange 13 of the cover engage annular grooves in the key guide and since the lower face of the key guide is larger than the upper face, it is impossible to forcibly remove the guide thru the upper face of the flange 13. As an added protection for the lock, a circular steel plate 47^a, having an aperture for the key, is secured to its upper end to protect that part of the lock containing the tumblers. The rotating element of the lock 46 has a cam 55, Figure 6, mounted upon its lower end. A stud 56 projecting from the cam will, when the cam is rotated by the lock key, be brought into engagement with an inwardly directed projection 57 which is integral with a lower locking ring 48. A resilient pin 58 is mounted in the ring 6 on the opposite side of the projection 57 from the stud 56. The cam on the opposite side from the stud 56 is formed into a beveled shoulder 59 which will engage a shoulder on the resilient pin 58, when the cam is rotated to lift the pin. When the lower locking ring is in the locked position it cannot be moved to the unlocked position without a key, as such movement is prevented by the pin 58. It will be evident, however, that when the cam is rotated by a suitable key, the pin 58 will be retracted into ring 6 and permit, upon further rotation of the cam, the movement of the lower locking ring 48 to the unlocked position by means of the stud 56. The lower locking ring 48 is circular in form and is slidably mounted in a groove in the bottom of ring 6. An upper locking ring 15 is rotatably mounted in a groove in the upper portion of ring 6 and is connected to the lower locking ring by means of spacers 50 which will hold the locking rings in a fixed relative position to each other at all times. Thus it will be seen that any movement of the lower locking ring will produce a coincident movement of the upper locking ring. The upper locking ring is provided with an inwardly directed projection 51 having a straight edge 52 on one side which engages when rotated, in slot 53 (Figure 4) of the locking pin 40 and locks the cover 5 to the ring 6. A tension spring 54 having one end secured to the locking ring 15 and the other to the ring 6

will rotate the locking rings clockwise to the locking position.

The normal operation of this device consists of unlocking the cover by means of a proper key, which is inserted into the lock and turned in the proper direction. The turning of the key will cause the locking rings to disengage from the grooves in the locking pins and permit the cover to be forced away from the mounting ring a slight amount by the springs 37 and 44, so that the locking ring cannot again engage the grooves in the locking pins. The key is removed from the lock. The cover may then be retracted further from the mounting ring and rotated to its natural hanging position for exposing the combination dial. After the vault door has been unlocked it is desirable to close the cover again to prevent unauthorized tampering with the dial or a premature locking of the vault door.

When used as a protective device to guard against a forcible attempt to gain access to the dial; the door is closed and locked, and the cover locked over the combination dial. In this position, if a forcible attempt is made to get at the dial, either the ring 6 is shifted or the cover will be forced toward the ring 6. If the ring 6 is shifted the contracted portions 11 of the screws 9 are sheared and the springs 32 will force the heads of the screws 9 against the hammer pins 27 which forces the firing pins 25 against the caps in the cartridges 24, thus firing the cartridges and vaporizing the repellent liquid. If an attempt is made to gain access to the dial by a blow on the cover 5, the stop pins 36 and 43 will puncture the frangible tops of the screw plugs 38 and 45 respectively, thus permitting the cover, the cartridge and firing pin to move towards the ring 6 through the space 39. Since the hammer pin 27 cannot be moved in a downward direction, the result will be to force the firing pin 25 upwardly against the cartridge 24, thus causing it to be fired and the repellent liquid thereby vaporized.

We are aware that numerous details of construction may be varied through a wide range without departing from the principles of this invention, and we therefore do not purpose limiting the patent granted, otherwise than necessitated by the prior art.

We claim as our invention:

1. In a lock protecting device, a mounting ring for surrounding the controlling element of a lock mechanism, a lock cover interfitting with said ring, means for holding said cover in spaced relation to said ring, locking means for securing said cover to said ring, a noxious material contained in said cover, means in said cover for vaporizing said material, and means in said ring adapted to energize said vaporizing means upon either a shifting movement of the ring or downward movement of said cover from the locked position.

2. In a lock protecting device, a mounting ring for surrounding the controlling element of a lock mechanism, a lock cover interfitting with said ring, means for holding said cover in spaced relation to said ring, locking means for securing said cover to said ring, a noxious material contained in said cover, means in said cover for vaporizing said material, and means adapted for energizing said vaporizing means upon movement of said cover.

3. In a lock protecting device, a mounting ring for surrounding the controlling element of a lock mechanism, a lock cover, locking pins for securing said cover to said ring, said ring having apertures therein for receiving said locking pins, frangible stop means cooperating with said locking pins to maintain said cover in spaced relation to said ring, a noxious material sealed within said cover, and means in said cover for vaporizing said fluid when said stop means is broken by impact upon said cover.

4. In a lock protecting device, a mounting ring disposed adjacent to a lock controlling mechanism, a cover secured to said ring, a noxious material contained within said cover, cartridges carried by said cover adapted when fired to vaporize said noxious material, a firing plunger having a frangible section, spring means for moving said plunger to firing position when the frangible section is broken by a movement of said ring.

5. In a lock protecting device, a mounting ring connected to a sustaining element, a cover secured to said ring, a noxious material within said cover, means in said cover for vaporizing said material, and means extending between said ring and its sustaining element adapted to energize said vaporizing means when said ring is moved relative to its sustaining element.

6. In a lock protecting device, a base ring adapted for mounting upon a sustaining element, a cover secured to said ring, a noxious material within said cover, means in said cover for vaporizing said material, means for energizing said vaporizing means, said last means serving to normally secure the base ring to said sustaining element and releasable from said normal position upon movement of said ring.

7. In a lock protecting device, a mounting ring surrounding the controlling element of a lock mechanism, a lock cover interfitting with said ring, locking pins having a groove secured to said cover, apertures in said mounting ring for receiving said locking pins, a locking ring within said mounting ring, and key means for moving said locking ring into the groove of the locking pin for securing said cover to said mounting ring.

8. In a lock protecting device, a mounting ring surrounding the controlling element of a lock mechanism, a lock cover interfitting with said ring, locking pins secured to said

cover, locking rings adapted upon rotation to engage said pins and secure the cover to said mounting ring, and means for locking said locking rings in engagement with said pins.

5 In testimony whereof we have hereunto subscribed our names at Chicago, Cook County, Illinois.
